PORTABLE BOAT

John H. Thedick, Oakland, Calif.

Application February 28, 1947, Serial No. 731,537

2 Claims. (Cl. 9—2)

1

This invention relates to boats, and more particularly to a boat of the portable knockdown type wherein the separable sections may be conveniently and compactly nested together for purposes of transporting the boat to and from its site of use.

The principal object of the invention is to provide a boat comprised of a plurality of interfitting sections adapted to be pressingly held in abutting relation by a plurality of cables, said cables having associated therewith novel means for maintaining them under tension to render the boat seaworthy.

Another object of the invention is to provide a knockdown boat embodying a plurality of separable sections, said sections and the accessory members thereof being so formed as to allow of a nesting of the sections to provide a compact box-like package which may be readily carried by hand or stowed in a limited space, such as the trunk of an automobile, or the like.

A further object of the invention is to provide a boat comprising a plurality of individual hull sections composed of waterproof plywood or of a molding plastic, said sections being thus provided with such strength in relation to weight that the use of bulkheads intermediate of the sections is obviated.

And still another object of the invention is to provide a portable boat comprising a plurality of separable individual hull sections so arranged and secured together that added hull sections may be selectively added to provide a boat of a desired length and load carrying capacity.

Other objects and advantages of the invention will be apparent from the following description taken in conjunction with the drawings forming part of this specification, and in which:

Figure 1 is a plan view of the portable boat embodying the invention;

Figure 2 is a view in elevation of the boat of Figure 1;

Figure 3 is a view in front elevation of the portable boat;

Figure 4 is a detail view in perspective showing portions of two adjacent hull sections of the boat;

Figure 5 is an enlarged detail view in elevation of one of the two cable securing elements affixed to the stern section of the boat;

Figure 6 is a view taken along lines 6—6 of Figure 5;

Figure 7 is an enlarged detail view in plan of one of the forward cable-tensioning members; and

2

Figure 8 is a view in perspective of the boat sections compactly arranged for carrying.

Referring to the drawings for more specific details of the invention, the boat is comprised of a bow section 10, a semi-bow section 12, an intermediate section 14, and a stern section 16, each of said hull sections having a substantially U-shaped transverse rib 18 at the ends thereof adjacent the other sections. Oppositely disposed lower ribs 20 are provided for each of the boat sections, said ribs for the sections 12 and 14 being secured to the transverse ribs 18 of said sections, and said ribs for the sections 10 and 16, respectively, being secured to a bow post, not shown, 15 and the rib 18, and to the rib 18 and a stern plate 22. Over the framework provided by the ribs 18 and 20, the bow post and the stern plate 22, there is secured to each individual boat section a hull skin of waterproof plywood or molded plastic to provide side walls 24 and a floor 26.

Oppositely disposed gunwale lengths 28 are secured to the outside of the side walls 24 of each of the boat sections at the upper edge thereof. The transverse rib 18 of stern section 16 and 25 the forward transverse ribs of the sections 12 and 14 have secured to each of the upper edges thereof a holding clamp 30, while said ribs are also provided with a pair of dowel pins 32, adapted to be received within a pair of dowel pin holes 34, in the ribs 18 in juxtaposition thereto. The clamp and dowel pin bearing ribs 18 have embedded in a peripheral groove in one face thereof a rubber cable-type stripping 36 adapted to seal the abutting ribs 18 against the passage 35 of water therebetween when the boat sections are forcibly held together in a manner which will hereinafter appear.

A rear seat 38 supported by clips carried by the stern plate 22 and by hinged legs, not shown, pivotally secured to the front edge of rear seat 16; a center seat 40 supported by two foldable legs 41 pivotally secured to one edge of seat and by a removable cross bar 42 fitting into notches, not shown in rib 18 of hull section 14; a cowl plate 45 43 affixed across the gunwales 28 of bow section 10; removable oarlocks 44 secured to the side walls 24 of section 14; and deck boards 46 coterminous with the upper edges of the transverse portions of ribs 18 are also provided as conventional elements of the boat structure.

Inwardly extending recesses or wells 48 and 50 in the side walls 24 and floor 26, respectively, of the bow section 10 have mounted for rotation therein a sheave 52, while pivotally secured at the mouth of each well by a pin 54 is a lever 56 hav-

ing a sheave 58 rotatably supported at the end thereof. Each of the wells 48 and 50 has a forwardly and angularly inclined wall 51. Stainless steel, bronze or steel wire cables 60, are secured to the section 10 immediately forward of each of the wells 48 and 50, as by clamps 62 secured on bolts 64 carried by the section 10 by nuts 66, said cables extending between the sheaves 52 and 58 and having their free ends clamped between blocks 68 and 70 secured together by screws 72.

Four angle plates 74 are secured by screws 76 to the end of the stern section 16, one pair of said plates being located at the upper edge of the side walls 24 and the other pair being located at the outer edges of the floor 26. Each of the plates 74 has a pair of spaced wedge-like cleats 78 integral therewith.

In assembling the boat sections, the sections are successively aligned by fitting the dowel pins 32 of the ribs 18 into the dowel pin holes 34 of the adjacent ribs 18, and by simultaneously fitting the clamps 30 over the upper ends of the adjacent ribs 18. The clamps 30 and dowel pins 32 serve to maintain the sections of the boat against unalignment while the cables 60 are extended to lie against the outer surfaces of the walls of the sections between the gunwales 28 and guide ribs 80 carried by the section 12 and to lie against the underside of the hull. The free ends of the cables are extended between the spaced cleats 78 of the angle plates 74 and the blocks 68 and 70 secured to the ends of the cables are placed against side plates in position to be prevented from forward movement by the cleats 78. The cables, when in this position, have approximately one-half inch of slack length. The pivoting of the four levers 56 from the dotted line position of Figure 7 to the solid line position is effective to urge the cables inwardly of the wells 48 and 50, as shown, to lie along the walls 51 of said wells, thus placing each of the cables under a high tension, said tensioning of the four cables serving to uniformly urge the boat sections into tight engagement to compress the rubber striping 36 between the ribs 18 and provide a watertight boat. It is to be noted that the inner end of the wall 51 of each recess serves as a stop member for the sheave 58 to maintain the cable 60 under a maximum degree of tension, and that the tension of the cable 60 is effective to maintain the sheave 58 against the wall 51, said cable thereby serving to maintain itself under a maximum tension.

Added intermediate sections, similar in form to the section 14, may be added between said section 14 and the stern section 16 to vary the length and load carrying capacity of the boat.

The recessing of the sheaves 52 and 58 within the wells 48 and 50 serves not only to protect the sheaves from damage to which they would be vulnerable if they protruded from the sides and bottom of the hull, but also serves to enhance the external appearance of the sides of the hull and to obviate drag which would normally result if the sheaves protruded from the underside of the hull. The recessing of the sheaves also makes it possible for the cables to lie in tight engagement with the surfaces of the boat sections, thus enhancing the overall binding effect of the cables, and allowing the side cables to be sheltered by the gunwales 28.

To disassemble the boat after use, the boat is pulled ashore, and the levers 56 are pivoted to the dotted line position of Figure 7, thus pro-

viding enough slack in each of the cables to allow the blocks 68 and 70 on the rearward ends of the cables to be disengaged from the cleats 78 of the angle plates 74. The sections of the boat 5 may then be separated, the seats 38 and 40 and the oarlocks 44 removed, and, while the deckboards 46 are still in place, each of the sections 10 may be nested within the next rearward section, as indicated in Figure 8. After the sections are thus nested, the stern plate 22 and the side walls 24 of the stern section 16 form three sides of a substantially rectangular box. The rear seat 38 is then brought into position to constitute the fourth wall and is secured in position by clamps 20 on the underside thereof fittable over the transverse portion of rib 18 of the stern section. Handles 82 may be provided on the side walls 24 of the stern section for carrying purposes, and a cover board 84 having end straps 86 adapted to be secured to the handles 82 is preferably provided to retain the nested sections in place and to form a closed box-like structure.

While the preferred embodiment of the invention has been shown and described, it is understood that the embodiment is subject to modification, within the spirit of the invention and the scope of the appended claims.

What I claim as new and desire to secure by Letters Patent is:

1. For a knockdown boat having a plurality of separable hull sections including a bow section, a stern section, and intermediate sections, means for holding said sections in abutting relation under uniform pressure comprising a plurality of flexible cables each having one end thereof secured to the bow section, means carried by the stern section for anchoring the opposite ends of said cables against movement toward the bow section, an elongated recess in a hull section adjacent underlying of the cables, a sheave rotatably mounted within each recess having its peripheral edge substantially conterminous with the mouth of the recess and adapted to be engaged by the adjacent cable, a first class lever eccentrically mounted for pivotal action at the mouth of each recess, a rotatable sheave mounted on the working arm of said lever, and overlying the cable, said latter sheave being effective upon a pivotal movement of the lever in one direction to travel on the cable and enter the recess to laterally displace a portion of the cable from its unstressed position and force said portion within the recess to place the cable under tension.
2. Means, as specified in claim 1, for locking a plurality of hull sections of a boat together, wherein the forward wall of each recess is angularly inclined toward the forepart of the hull section, said cable being adapted to lie in engagement with said wall, and the inner end of said wall being adapted to serve as a stop member for the sheave carried by the lever to maintain the cable under a maximum of tension.
